CLAIM

The ornamental design for a projector, as shown and described.

DESCRIPTION

1. Projector
- 1.1 : Perspective
- 1.2 : Front
- 1.3 : Back
- 1.4 : Left
- 1.5 : Right
- 1.6 : Top
- 1.7 : Bottom

The present ornamental design is a combination of the shape and pattern of a projector as shown and described; the broken lines indicate unclaimed portion of the article that form no part of the claimed design.
